UNITED STATES PATENT OFFICE

1,996,505

LIQUID EXPRESSER

Louis F. Ducker, Orlando, Fla., assignor to Richard A. Kaps and Charles H. C. Van Pelt, both of Cincinnati, Ohio, and Louis F. Ducker, as trustees

Application September 25, 1930, Serial No. 484,418
Renewed August 13, 1934

6 Claims. (Cl. 68—37)

My present invention is an elaboration of the invention shown, described and claimed in my application for letters patent for improvement in liquid expressers, Serial No. 476,892, filed in the 5 United States Patent Office August 21, 1930.

Liquid expressers of this character are employable in expressing liquid from laundry and from material which has been dry cleaned. It is also applicable for expressing liquid from 10 cloths, rags and similar articles used in the household and for other purposes.

The liquid expresser comprises a material chamber for receiving the material from which the liquid is to be expressed, and a pressure 15 chamber for receiving the fluid pressure agency by which the liquid is expressed, there being a flexible wall between said chambers, which wall may be in the form of a bag, and is hereinafter referred to as a bag.

It is the object of the present invention to 20 provide novel means whereby to secure the flexible bag in place; further, to provide novel means whereby to form a fluid tight joint between the flexible bag and the member to which it is attached; and, further, to provide novel means 25 whereby to secure the flexible bag between the body and cover of the tank.

It is the object of my invention further to 30 provide novel clamping means for clamping the movable member or cover of the device in place.

It is the object of my invention further to 35 provide novel means whereby to introduce liquid into the material chamber; further, to provide novel means for introducing liquid into one end of the material chamber by means of a flexible conduit extending lengthwise of the material chamber and to provide for outflow of the liquid at the other end of the material chamber; and, further, to provide a flexible bag arranged for 40 receiving the material, in which bag the material is squeezed for expressing the liquid therefrom, the liquid passing out at one end of the bag, and a flexible conduit communicating with the other end of the bag and arranged to shift in conformity with the shifting of the wall of the bag while maintaining its fluid connections.

It is the object of my invention, further, to 45 provide novel means whereby to rinse the material; and, further, to provide novel means for supplying a qualifying agent, such as bluing, to the material.

The invention will be further readily understood from the following description and claims, and from the drawings, in which latter:

Fig. 1 is a side elevation of an exemplifying de-

vice, embodying my invention, shown in association with a washing machine and a stationary tub, partly broken away.

Fig. 2 is a plan view of the same.

Fig. 3 is a detail sectional view, taken on the line 3—3 of Fig. 2.

Fig. 4 is a vertical section of my improved device, taken on the line 4—4 of Fig. 2, showing the tank closed, and the material and the bag in pressed relation, and partly broken away.

Fig. 5 is a plan view of the same, partly broken away.

Fig. 6 is a side elevation of the upper portion of my improved device.

Fig. 7 is a cross-sectional detail view, taken on the line 1—1 of Fig. 2.

Fig. 8 is a cross-sectional detail view, taken on the line 8—8 of Fig. 5.

Fig. 9 is a cross-section of my improved device, taken on the line 4—4 of Fig. 2, showing the device in open relation.

Fig. 10 is a side elevation showing an enlarged detail view of the clamping means for the flexible bag in release relation, partly broken away.

Fig. 11 is a plan view of the same.

Fig. 12 is a cross-section of the same, taken on the line 12—12 of Fig. 10.

Fig. 13 is a vertical cross-section, showing a modification of my improved device, taken in the plane of the line 13—13 of Fig. 14.

Fig. 14 is a cross-section of the same, taken in the plane of the line 14—14 of Fig. 13; and,

Fig. 15 is a vertical section showing a container for a qualifying agent, such as bluing, in association with my improved device, and taken in the plane of the line 15—15 of Fig. 5.

In the present exemplification of my invention there is a tank 21 in which there is a bag 22, the bag receiving the clothes or other material from which the liquid is to be expressed, a body 40 or batch of such material being shown at 23 in the bag. (Figs. 4 and 9).

The bag is provided with a bead 25 about its mouth 26. The bag exemplified is of greater length than diameter. The tank is provided with an annular groove 27 in which the bead 25 of the bag is received. (Figs. 3, 9, and 13). This groove is provided with a lower wall 28, an upper wall 29 and an outer wall 30. (Fig. 3).

Means are provided for squeezing said bead 50 into its groove for forming a fluid tight joint. These means are exemplified as a ring 33, shown as a split ring, provided with clamping means 34. (Figs. 9, 10, 11 and 12). The ring is shown as an annular ring having a slight cross-sectional 55

Fig. 1 is a side elevation of an exemplifying de-

incline toward the bottom and middle portion of the tank. It has an outer support 35, shown as an outwardly extending flange arranged to rest on the lower wall 36 of an outward bulge 37 of the tank, forming an annular flange about the mouth 38 of the tank. (Figs. 3 and 9).

The clamping means for the ring is exemplified as a wedge-piece 41, received between oppositely inclined end walls 42, 43, at the split 44 in the ring. (Figs. 10, 11, 12). There is a dove-tail connection 45 between each end of the wedge-piece and the respective ends of the split ring for holding the parts in line with each other. A screw 46 has a head 47, a washer 48 being received between the respective ends of the split ring and the head for spanning the split between said ends. The screw has threaded connection in a threaded socket 49 in the wedge-piece.

When the screw is turned to clamp the ring, the wedge-piece is forced between the ends of the split ring for spreading said ends, thereby enlarging the diameter of the ring, and causing lateral pressure of its outer annular face 50 against the bead 25, for crowding the bead into its groove, and causing intimate contact between the major portion of the cross-sectional circumference of the bead and the wall of the groove, the upper portion, the lower portion and the outer portion of said wall of the groove together with the ring substantially encompassing the bead. (Fig. 3).

The bead is squeezed cross-sectionally into said groove by reason of the lateral pressure thereon for forming intimate contact between it and the wall of the groove throughout the major portion of the bead, preventing leakage past said bead when pressure is applied on the outside of the bag.

The bead is shown rounded in cross-section and as having the depending portion of the bag depending from the inner portion of the bead. The outer face of the split ring is normally spaced from the tank by an annular space for permitting its expansion.

The tank comprises a pressure chamber 55 and a material chamber 56 between which the flexible wall exemplified as the bag 22 is located. (Figs. 4 and 9).

The flexible bag is preferably rendered impervious to the pressure medium and to the liquid in the material operated on. The flexible bag may be of resilient material. It may for instance be of soft pliable rubber similar to the rubber of an inner tube of an automobile tire and provided with an integral thickened solid rubber lip or bead by means of which it is secured to the tank. The flexible bag may be reinforced by a layer or layers of fabric, or the bag may be a woven or other fabric permeated or coated with rubber or with other substance impervious to the liquid in the material and the pressure agency, although other materials may be employed.

It is desirable that the bag be flexible so as to readily yield in all its portions in any direction to the fluid pressure thereon.

The tank is provided with a wall 57, extending upwardly from the bulge 37. There is an inwardly and downwardly extending deflector 58 at the upper end of the wall 57 about the mouth of the tank. (Figs. 4 and 9).

The tank comprises a body portion 61 and a cover 62. The cover is preferably supported so that it may be readily centered with relation to the mouth. Thus a yoke 63 is connected by a hinge 64 with the tank. (Figs. 4, 5, 6, 9). It is shown comprising side bars 65 which may be formed of sheet metal and rigidly secured to-

gether as by rivets 66. The side bars have flanges 67 at one end, forming hinge members through which the hinge pintle 68 is received, the pintle being also received through a bearing in a hinge member 69 fixed to the tank.

The pintle connection is preferably loose, as by providing slots 70 in the flanges 67 in which the pintle is received, to permit slight shifting of the cover to center the cover. Stops 71, 72, respectively on the yoke and the tank, limit outward movement of the yoke and cover. (Figs. 5 and 6).

The cover 62 has an upwardly extending central boss 74 received in a slot 75 in the yoke, and pivoted to the yoke by a pivot pin 76, so as to suspend the cover pendulumwise from the yoke. The cover is provided with an annular seat 77 received in the ring 33. This seat preferably tapers inwardly and downwardly so that its inner end may be readily received in the ring 33 for coaction between the annular seat 77 and the inner annular face 78 of the ring. (Figs. 4 and 9).

A firm seating between said faces is not essential. The friction between the ring and the flexible wall or bag 22 preferably exceeds the frictional resistance between the cover and said ring, so that the cover may be manipulated in the ring and out of the ring without disturbance of the ring.

The swinging end of the yoke is provided with a handle 79 fixed between flaring flanges 80 of the yoke.

The tank is provided with a hook 81. A loop 82 is received about the hook, the respective sides of the loop having pivot connections 83 respectively with the two arms of a lever 84, pivoted on a pivot pin 85 to the yoke, and having a handle 86. (Figs. 5, 6, and 8). The relations of the pivots 83, 85, to each other and to the hook are such, that when the lever 84 is swung into release position, the engaging portion of the loop engaging with the hook is distanced a greater distance from the pivot 85 than when the clamping lever 84 is moved into clamping position.

During the clamping movement the pivot 83 is moved about the pivotal axis 85 for shortening the distance in a right line between the pivot 85 and the hook, and thereby clamping the yoke and the cover supported thereby toward the tank. When the cover is in clamped position, as exemplified in Fig. 6, a right line between the pivot 83 and the hook is at that side of the pivot 85 toward the handle 86, whereby the yoke and the cover are locked to the body of the tank, the handle 86 resting on the yoke when the clamp is in locked position.

Fluid under pressure is admitted into the pressure chamber. This fluid may be water from a usual house faucet 81.

The tank may be suitably supported, as by means of a bracket 92 extending from the frame 93 of a usual washing machine 94. The bracket has a seat 95, shown as a ring, in which the body of the tank is received and supported, lugs 96 on the tank resting on the bracket. (Figs. 1 and 6).

The tank is rotatively supported on the bracket so that its spout 97 may be directed into various radial positions, for instance above the tub 98 of the washing machine, above the stationary tub 99, or into intermediate positions above a suitable tub or basket placed thereunder.

The tank is provided with a port 101 from 75

which a nipple 102 extends. A flexible hose 103 is fixed to said nipple and has on it a member 104 of a coupling, the other member 106 of which is secured to the faucet 91.

The coupling is preferably a slip coupling, the members of which are readily connected and disconnected.

One of the members of the slip coupling (see the member 104, in Fig. 2) may for instance be provided with bayonet slots 109, the other member thereof (see the member 106 in Fig. 1) being provided with pins 110 received in the slots, for clamping a resilient washer 111 as in Fig. 7, between the shoulders 112 and 113 shown on similar members 128, 129 in Fig. 7. (Figs. 1, 2 and 7).

When the hose 103 is coupled to the faucet and the faucet is opened, water under pressure of the water service is admitted into the pressure chamber 55, for squeezing the flexible bag and the material therein. The water in the pressure chamber may be released by uncoupling said coupling and draining the pressure chamber through the hose into the stationary tub or a suitable receptacle or drain.

The cover 62 is provided with holes 117 through which the liquid in the material is expressed when squeezing the material. The cover is preferably provided with a shoulder 118 located above and preferably contacting the ring 33 for resisting dislodgment of the ring by pressure in the pressure chamber. (Figs. 3, 4 and 9).

A shield 121 is located above the cover so as to deflect the liquid proceeding from the holes. The boss 14 is provided with a shoulder 122. The shield is provided with a hole through which the upper end of the boss extends, the margin of the hole being secured to the shoulder. The shield and the top of the cover preferably slant toward the outer circumference thereof toward a gutter 124 formed by the bulge 31, the upwardly extending wall 57, the ring 33, and the outer edge of the cover. The upwardly extending wall 57 has an opening 123 therein between the gutter and the spout.

The gutter directs the expressed liquid toward the spout 97, whence it is discharged. The deflecting flange 58 prevents projection of the expressed liquid beyond the device and deflects the liquid downwardly toward the gutter.

A liquid feeding means for feeding liquid into the bag is provided, as by providing the cover with a port 125 provided with a nipple 126. Liquid is supplied into the bag by means of a hose 127 arranged to be attached to the faucet 91 so as to cause flow of the water from the faucet into the bag. The connection between the hose and the cover may be made by suitable slip coupling similar to the slip coupling 104, 106, having coupling members 128, 129, respectively on the nipple 126 and the hose 127, and the connection between the hose and the faucet may be made by providing the end of the hose with a slip coupling member 130 coacting with the slip coupling member 106 on the faucet.

In order to cause permeation of the material in the bag by the liquid introduced thereto, I prefer to lead the incoming liquid into the bottom portion of the bag and to cause flow of the liquid toward and through the top of the bag, employed in rinsing the material or when supplying the same with a qualifying agent, such as bluing.

A flexible conduit 133 is suitably attached to the inner end of the port 125 and extends downwardly into the bag and has its discharge end 134 preferably in the bottom of the bag.

This conduit may be a soft rubber hose and be very pliable and collapsible, and in practice preferably lies next to the wall of the flexible bag and is readily pressed with the flexible bag into various shapes so as to follow the contours of the material bearing against the same and of the bag while expressing liquid from the material.

The port 125 is preferably adjacent to the hinge portion of the cover and the inner conduit 133 is preferably provided with a movable section 135 which may move with the cover and be extended without danger to its connection with its port and without disturbance of the position of the main portion of the conduit in the bag.

The nipple 126 is provided with an inner enlargement 137 placed in the upper end of the hose, the upper end of the hose and the enlargement being received in a seat 138 in the inner face of the cover, the upper end of the hose being clamped between the enlargement and the seat for forming a fluid tight joint. A shoulder 139 between the nipple and the cover limits this clamping action.

The cover has a boss 140 through which the nipple extends, the nipple passing through a hole 141 in the shield. Cushion washers 142, 143, are at the respective sides of the shield about the nipple. The coupling member 128 is threaded about the nipple, and clamps the parts together. (Fig. 7).

Liquid in the material is expressed by the connection of the port 101 with the faucet 91, and the opening of the faucet, so as to admit fluid under pressure into the chamber 55, thereby pressing upon the bag, preferably at its sides and at its end, for squeezing the bag and the material therein and causing the liquid therein to be expressed, as through the holes 117, the expressed liquid flowing over the spout 97.

If it is desired to rinse the material, the port 101 is disconnected from the faucet and the fluid in the pressure chamber allowed to be discharged, whereby the bag and the material therein drop in the pressure chamber. (The port 125 is then connected with the faucet and the rinsing liquid admitted through the port 125 and the hose 133 into the bottom of the bag, whence it flows upwardly through the material, permeating the various portions of the material, aiding in loosening the material, and flowing through the pores of all the material, being discharged through the holes in the cover and across the spout, carrying with it any residue of soap or other detergent and other loose ingredients or matter in the material for cleansing the material and rinsing the same.

The connections of the ports 101 and 125 may be reversed one or more times for alternately charging the material with fresh liquid and squeezing the material for expressing the liquid therefrom.

I have provided means whereby a qualifying agent such as bluing may be introduced into the material. Thus a container 147 for the qualifying agent may be provided in the liquid supply for the bag. (Fig. 15).

The container comprises a casing 148 having an inlet port 149 and an outlet port 150, a valve 151 normally closing the outlet port. (Fig. 15). One of the ports is provided with a coupling member 152 complementary to the coupling member 128, the other port being provided with a coupling member 153 complementary to the coupling member 129 on the hose 127, forming slip

couplings for readily affixing and removing the container.

The container may be located at any suitable point between the faucet and the cover. 5 I have exemplified the same located between the outer end of the hose 127 and the cover.

A pipe 155 connects with the inlet port 149 and extends to a point near the outlet port 150. (Fig. 15). There is a space 156 between the end 10 of the pipe 155 and the outlet port. The pipe 155 is provided with holes 157. When the valve 151 is opened and flow of water proceeds through the hose 127 from the faucet, the water flows through the pipe 155 across the space 156, drawing 15 the qualifying agent, such as bluing, with it out of the container for modifying the water and mixing it with the material in the bag. A portion of the water flows through the holes 157 into the container for aiding in mixing the 20 qualifying agent with the water.

The qualifying agent is mixed with the water as the water is injected into the material, as by 25 syphoning or injecting the bluing into the water flowing into the material. When using bluing, the bluing is premixed so as to have all particles 30 of the bluing dissolved. The bluing solution in the container is stronger than the solution when introduced into the material, the water mixing with the bluing solution in the container for weakening the bluing which is introduced into the bag.

The flow of the bluing solution is continued through the bag, the bluing solution mixing with the rinsing water last in the bag, the inflow of 35 the bluing solution gradually displacing the rinsing water in the bag. The inflow of the bluing solution is continued until the outflow of the liquid from the spout shows flow of bluing water of proper color from the bag, whereupon the 40 faucet as well as the valve 151 are closed, the material is permitted to remain in the bluing water until it is thoroughly soaked, whereupon the bluing water is expressed by pressure in the pressure chamber 55.

45 If desired, the container 147 may be removed and the hose 127 connected with the nipple 126, so as to cause rinsing water to pass through the material after the bluing.

The container for the modifying agent is 50 readily attached to and released from its connections in the conduit between the faucet and the cover.

In a modification shown in Fig. 13 the conduit 55 133 is for its major portion fast with the bag. In this modification one wall of the conduit is formed by the wall of the bag, the other wall of the conduit being formed by a flexible strip 161, the edges of which are fastened to said wall, leaving the passage of the conduit between said flexible strip and said wall. The lower end of the passage has the outlet 134 in the bottom of the bag.

The upper end of the conduit may be extended as a hose section 162, similar to the hose-section 60 135, one end of which has connection with said strip and said wall, and the other end of which is secured to the cover in manner similar to the securing of the hose-section 135 to the cover.

In employing my invention, the ring 33 is expanded by means of its expanding means 34 for 70 clamping the mouth end of the bag in place, and forcing the annular bead at the mouth end of the bag into its groove for forming a fluid tight seal between the bag and the tank. This connection 75 may be maintained throughout the life of the bag,

but may be released for repair and attention to the parts.

The end section 135 of the hose 133 is folded under the cover when the cover is closed and readily adapts itself to open relation of the cover 5 without strain upon the hose or the bag.

The cover is swingingly supported on the yoke, and moves with the yoke. It is readily moved into open relation, as its connection with the ring 33 is preferably a loose connection for permitting 10 ready insertion and removal of the cover in the ring.

The material is introduced into the bag, as from the tub of the washing machine, or the stationary tub, or a suitable container, across the spout 97, 15 the spout draining excess liquid flowing thereon back into the receptacle from which the material is received.

When the bag has been filled, the cover is closed by grasping the handle end of the yoke 20 and swinging the yoke for positioning the cover above the mouth of the tank. Ready centering of the cover with relation to the mouth is obtained by a slight yielding in the hinge of the yoke.

25 The lower contracted end of the cover is readily received in the upwardly tapered widening mouth of the tank. When the cover has been properly centered, the yoke is depressed by pressing upon the handle 79 thereon for urging the cover into its 30 seat. The loop 82 is placed about the hook 81 and the lever 84 is swung on its pivot 85, thereby raising the pivot connection 83 of the loop with said lever, for clamping the yoke toward the tank and moving the cover toward the ring and placing 35 the flange 118 of the cover into obstructing relation with said ring, so as to prevent outward movement of the ring and release of its clamping relation upon the mouth of the bag during the 40 expressing of the liquid from the material in the bag.

The connections between the faucet 91 and the port 101 in the tank having been made by attachments of the respective ends of the hose 103, and the faucet having been opened, the water from the hydrant under pressure is received in the pressure chamber 55 about the bag and against the end of the bag for squeezing the bag and the material therein, and exerting an equal pressure upon all portions of the material, 50 for squeezing the liquid out of the material throughout the whole of the body of the material, and bringing the material to an equal state of dryness throughout its batch.

The water from the faucet in the pressure 55 chamber exerts equal pressure throughout the outer face of the bag and causes the various portions of the bag to conform to the shape of the outer surface of the batch of material when in squeezed condition. The bag is contracted 60 during the squeezing operation, thus avoiding expanding strains upon the bag, and permitting the bag to readily crumple or bunch about the material, and avoiding stretched relation or danger of puncturing the bag.

65 The conduit 133 is collapsed by this pressure and adapts itself to the squeezed form of the bag, forming little or no resistance to the squeezing pressure in the pressure chamber.

The liquid squeezed from the material passes 70 through the holes in the cover, into the gutter 124, and thence over the spout 97.

When the liquid has been properly expressed out of the material, the faucet is closed, and the pressure chamber is allowed to drain, the hose 75

being released from the faucet and the end of the hose being placed over a suitable receptacle or drain for receiving the water flowing from the pressure chamber.

5 If rinsing of the material is desired, the hose 127 is attached to the faucet and to the port 125, and the faucet opened, whereby the rinsing water passes into the hose 133 and along the wall of the bag, being discharged into the bottom 10 of the bag, it being understood that the bag and the material therein will meanwhile have dropped after expressing the liquid therefrom.

The rinsing water takes an upward course 15 through the material, loosening the material, and causing separation of the layers of the material, causing the rinsing water to rise in the bag and to flow through all portions of the material and the pores therein, carrying with it the particles of soap suds, soap, soil and foreign 20 ingredients there may be in the clothes through the holes in the cover and across the spout.

Soap and similar ingredients which have been retained by the material naturally float on top 25 of the water, and in my improved device this water, together with the ingredients of soap and similar substances are forced away from the material through the top, so as to clear the same from the clothes. Passage of this rinsing water is upward in the direction of natural flow of the 30 soap suds, soap particles and other similar ingredients, for discharging such ingredients in the direction of their natural flow from the material and floating the scum formed by such ingredients away from the material.

35 This is materially distinguished from hand rinsing, in which the material is raised out of the rinsing bath and lowered into the rinsing bath, the top of the rinsing bath retaining the film or scum rinsed out of the material, so that 40 at each raising or lowering of the material this film or scum is again mingled with the material. In my improved device this is avoided and rinsing is quickly effected.

If it is desired to blue the material, the bluing 45 container 147, in which a suitably strong bluing solution has been placed, is connected in the conduit between the faucet and the cover. Upon opening of the faucet 91 and of the valve 161, water is forced through the container, taking up bluing in its passage for weakening the solution of bluing and feeding the weakened solution into the bottom of the bag, the weakened bluing solution mingling with any water that 50 may be in the bag, or if the material shall have 55 been pressed, the weakened bluing solution is received in the material.

The material is loosened and spread by the flow of the weakened solution of bluing, causing the bluing solution to impinge all surfaces of 60 the material and flow through the pores thereof for applying a uniform bluing solution to all portions of the batch of material in the bag.

When the operator perceives bluing water of 65 proper depth of color passing over the spout, the supply of bluing solution is stopped by closing the valve 161 and the faucet 91, and the material permitted to remain in the solution a suitable length of time, the liquid in the material being 70 then expressed by connection of the faucet 91 with the port 101 as hereinbefore explained.

75 My improved device is simple and economical in construction and operation, is quick in its functions, prevents breaking or tearing away of buttons and other attached objects, and prevents injury to the material and the flexible bag.

I do not herein claim the general arrangement of material chamber, pressure chamber and flexible wall or bag between said chambers, nor the relation nor forms of the same; nor the general structures and arrangements at the mouths of the bag and the tank; nor broadly means nor method for expressing the liquid, nor rinsing the material; nor broadly shifting the spout into various radial positions; having shown, described and claimed the same in my aforesaid application and in my application for letters patent on improvements in liquid expressers, filed in the United States Patent Office March 16, 1931, as Serial No. 522,981.

Having thus fully described my invention, what 15 I claim as new, and desire to secure by Letters Patent, is:

1. In a device of the character described, the combination of a receptacle, a flexible imperforate member therein dividing said receptacle 20 into a pressure chamber and a material chamber, said flexible member having a margin, said receptacle having a securing zone for said margin, said zone and said margin forming complementary walls, one of said walls being provided 25 with a bead and the other of said walls having a groove in which said bead is received, a split ring in the plane of said bead and said groove, and endwise pressing means acting on said split ring to change the diameter of said split ring for exerting lateral pressure between said bead and the 30 wall of said groove.

2. In a device of the character described, the combination of a tank comprising a cover, a flexible imperforate bag in said tank, said tank 35 having a pressure chamber at one side of said flexible bag and a material chamber at the other side of said flexible bag, the cover having an outlet for the fluid expressed from said material chamber, said tank having a groove provided 40 with upper, lower and outer walls, said flexible bag having a resilient bead in said groove cross-sectionally shaped to contact all said walls, a split ring inside said bag, and endwise expanding means between the ends of said split ring for 45 spreading said ends and increasing the diameter of said split ring for laterally pressing said resilient bead against all said walls of said groove.

3. In a device of the character described, the combination of a tank comprising a cover, a flexible imperforate bag in said tank, said tank having a pressure chamber at one side of said bag and a material chamber at the other side of said bag, the cover having an outlet for the fluid expressed from said material chamber, said tank 50 having a groove, said bag having a bead fitting in said groove, a split ring inside said bead, and means between the ends of said split ring for expanding said ring, and forcing said bead into said groove, and said cover being provided with a shoulder coacting with said ring to maintain said ring in said bead.

4. In a device of the character described, the combination of a receptacle, a flexible imperforate bag therein forming a pressure chamber at one side of said bag and a material chamber at the other side of said bag, liquid discharge means at one end of said bag, an inlet for said receptacle for the admission of a fluid under pressure in said pressure chamber to compress the bag and its contents for expressing liquid from the contents, and a liquid conduit extending lengthwise inside said bag and having a shiftable discharge mouth at the bottom of said bag, said 70 75

shiftable discharge mouth shiftable by said pressure.

5. In a device of the character described, the combination of a receptacle having a cover, a flexible imperforate bag in said receptacle forming a pressure chamber at one side of said bag and a material chamber at the other side of said bag and having a mouth adjacent to said cover, liquid discharge means adjacent to said mouth, liquid supply means for said bag having a supply port on said cover, and a flexible conduit in said bag having connection with said supply port and including a section movable with said cover.
10. In a device of the character described, a fluid pressure container having a fluid pressure

inlet, a fluid tight universally collapsible bag freely and bodily suspended within said container in a sealed relation thereto adapting the bag and its contents to be compressed by a fluid pressure admitted into the container about the bag, a cover confining the contents within the bag and provided with a sufficient area of portage for venting the water expressed from the contents when the pressure is administered, and a tube engaged through and carried by said cover and extending into the bag and to the bottom thereof for admitting a fluid into the bag to pass upwardly through the contents thereof.
